UNITED STATES PATENT OFFICE.

ISIDOR DEUTSCH, OF MONTREAL, CANADA.

POWER-TRANSMITTING DEVICE.

SPECIFICATION forming part of Letters Patent No. 726,517, dated April 28, 1903.

Application filed May 19, 1902. Serial No. 108,025. (No model.)

To all whom it may concern:

Be it known that I, ISIDOR DEUTSCH, a citizen of the United States of America, residing at Montreal, in the district of Montreal, Province of Quebec, Canada, have invented certain new and useful Improvements in Power-Transmitting Devices, of which the following is a specification.

My invention relates to improvements in power-transmitting devices; and the object of the invention is to provide a device in which the power will be transmitted from a revolving axle in a regular and positive manner and whereby the effect of any movement of translation in the axle will in no way affect the continuous and uninterrupted transmission of the movement and also which shall be economical in the matter of construction and wearing qualities; and it consists, essentially, of a hub, preferably split, bolted on a revolving axle and having projecting flanges, a gear-wheel in parts adjustably attached to the aforesaid projecting flanges, a sleeve surrounding the axle and extending from the gear-wheel, a coacting gear journaled in an arm from a strap encircling the sleeve, and a swinging support for the said arm, the various parts being constructed in detail, as hereinafter more particularly described.

Figure 1 is a view showing an elevation of a portion of the car truck and wheel with my device attached thereto. Fig. 2 is an elevation showing the obverse of my device. Fig. 3 is a plan view showing the general arrangement of the gearing and parts. Fig. 4 is a plan view showing an alternative form of gearing. Fig. 5 is a perspective view of one portion of the split hub from the interior. Fig. 6 is a perspective view of the other portion of the split hub from the exterior. Fig. 7 is a view showing the swinging support in elevation. Fig. 8 is a perspective view of one half of the gear and the sleeve extending therefrom viewed from the interior. Fig. 9 is a perspective view of the other half of the gear and sleeve viewed from the exterior.

Like characters of reference indicate corresponding parts in each figure.

a is the axle revolving with the car-wheel b. c is the split hub having the projecting flanges d and e. The hub c is bolted on the axle through the flanges e.

f represents slots extending through the projecting flanges d in radial lines from the center of the axle a.

55

g represents bosses adjacent to the outer end of the slot f and having threaded orifices in alignment with radial planes passing through the slots and through which are inserted the set-screws i.

60

h is a gear-wheel divided into two equal parts and having the sleeve j extending in halves from the said parts. The sleeve j has the groove k cut circumferentially in its periphery.

65

l represents stud-bolts rigidly fastened into the orifices m in the gear-wheel h and are designed to be located so that their centers are all on the circumference of a circle concentric with the outer circumference of the gear-wheel. The bolts l are designed to project through the slots f and to be held in one position therein by the set-screws i, whereby the gear-wheel h is securely held to the projecting flanges d. The bolts l in diameter 70 must be slightly less than the width of the slots f. The parts of the gear h in the sleeve j are further held securely together by suitable bolts through the orifices n and o.

75

p is a strap bolted around the sleeve j in the groove k, in which it is designed to have as little play as is consistent with good mechanical construction.

80

q is an arm projecting from the strap p and terminating in the rod r.

85

It must be here mentioned that it may not be necessary to support the arm q at so great a distance from the strap p.

s is a gear-wheel journaled in the arm q and designed to mesh with the gear-wheel h to rotate the shaft t.

90

u is a swinging support suspended by the links v from the cross-bar w. The links v are pivotally attached to the rings x, in which the rod y turns.

95

z is a thimble encircling the rod r between the rings x and turning with the rod y, to which it is rigidly attached.

The rod r is designed to project through the thimble z and is cushioned in front of and behind the said thimble with the spiral springs 2, which are suitably held at 3 and 4 to abut the ends of the thimble z.

100

In order to more clearly explain the utility,

I shall now describe the adjustment and operation. The inner sides of the split hub are carefully faced off after being bolted on the axle, so that the gear *h* may fit closely thereto, and the outer circumferential surface of the split hub is turned true, so that it may be concentric with tread of axle-wheels. The gear-wheel *h* is bolted securely to the split hub *c*, the latter forming the bearing for the said gear in its revolutions with the axle. The inner periphery of the sleeve *j* is not designed to bear on the axle at any part of its surface. The rotation of the gear *h* with the axle *a* turns the gear *s*, which is journaled in the arm *q* from the strap *p*.

It will be seen in the following explanations that the revolving of the sleeve will in no wise affect the position of the gear *s*. The positions of the sleeve *j* and the axle *a* must always be identical—that is, any vibration or sudden jar affects both—for the sleeve extends from the gear *h*, and this gear through the separable hub bears on the axle and turns therewith.

The adjustable and swinging support allows the truck and axle to have considerable lateral movement, which is extremely essential, as such lateral motion is constant and is especially emphasized in rounding curves. It will thus be seen that the rigidity of the arm *q* is much relieved.

The main object of this invention is to provide for the exact meshing of the teeth of the gear-wheels, notwithstanding the changes of positions of the axle and the truck while in travel. This is to a large extent accomplished by the adjustable support of the arm *q* through the turning of the rod *y* in the rings *x* and the consequent raising and lowering of the rod *y*. The springs *z* allow a limited lengthwise movement of the rod in the thimble *z* to account for the different vertical positions of the axle and the truck in relation to one another. It will be thus seen that at each circumferential movement of the sleeve the gear assumes a position relatively the same radial distance from the center of the axle. The gears are always in engagement one with the other, yet they are free to move with the changes in position of the truck or axle and still be in constant engagement.

The adjustment for the centering of the gear *h* in order that it may be concentric with the tread of axle-wheels is a very important feature in this device, and the means for accomplishing this are simple and effective and can be readily understood by any ordinary mechanic.

As before explained, the parts of the gear are bolted to the projecting flanges of the split hub through the slots *f*. This will allow the said bolts a considerable movement radially from the center of the axle. The movement of these bolts is controlled by the set-screws *i*, inserted through the bosses *g*, and as there is an intervening space between the

sleeve *j* and the axle, and therefore no bearing-surface directly from the gear, any movement of one of the bolts *l* in the slots *f* will change the position of the gear in relation to the center of the axle. In order to center the gear, the screws *i* must be regulated in turn until the distance between the outer circumference of the split hub and the center of each bolt-head in a direct radial line is exactly the same. The adjustment of the gear is then completed, and it will be found that the wheel is concentric with the tread of axle-wheels.

The difficulty hitherto experienced in centering of wheels is well known, and consequently the ease and facility with which by the simple turning of the set-screws the wheel may be centered will be much appreciated by mechanics and those otherwise interested. For instance, in this device a positive accuracy can be attained in a very short time by adjusting one screw after the other until they are, as before explained, equidistant from the circumference.

When the gear *h* is concentric with the axle, the strap *p* is bolted in a circumferential groove on the sleeve *j*, and, as explained heretofore, the gear is always at the same radial distance from the center of the axle, and therefore from the center of the sleeve and strap, for with the gear *h* they are concentric with the axle. Consequently the gear *s* may be engaged by the gear *h* equally well in the varying positions of the arm *q* caused by the jolting of the truck or the axle.

The shaft *t*, which is rotated by the gear *s*, extends into a dynamo or other machine requiring the power transmitted by the revolutions of the axle, and in extending this shaft it is probable that a universal or other suitable joint will be required intermediate of the distance between the dynamo and the gear. However, I have not shown this in my drawings, as it is well known and needs no further explanation.

In Fig. 4 I have shown a plan view of an alternative form of gearing, in which the arm from the strap is further extended, so as to form a bearing for the gear heretofore indicated, as *s*, in order that the said gear may engage the spur-gear instead of the bevel-gear *h* illustrated in the other drawings. The form of the swinging support and the general arrangement may be precisely the same as in that already described, and it must be here understood that I do not confine myself to any particular form of gearing, as many may be adopted using substantially the same arrangement.

The use of gearing for transmitting power from revolving axles in transit appears to be the only positive manner of transmitting power from the said axle, as there is no slipping, as in belts, and very little wear, and all the mechanism connected therewith may be suitably incased, so as to preserve it from the

inclemency of the weather, though this will not be as necessary with this device as in some of the others already known.

What I claim as my invention is—

- 5 1. In a power-transmitting device, the combination with a support and a car-wheel axle, of a hub having projecting flanges therefrom, a gear attached to the said flanges, a sleeve extending from the gear, a strap designed to 10 encircle the sleeve, a rigid arm on the strap, and a coacting gear journaled in the arm, as and for the purpose specified.
- 15 2. In a power-transmitting device, the combination with a support and a car-wheel axle, of a split hub having projecting flanges therefrom, a gear-wheel adjustably attached to said flanges, a sleeve extending from the gear and surrounding the axle, a strap designed to encircle the sleeve, an arm on the strap, 20 and a coacting gear journaled in the said arm, as and for the purpose specified.
- 25 3. In a power-transmitting device, the combination with a support and a car-wheel axle, of a split hub having projecting flanges provided with radial elongated slots, a plurality 30 of set-screws inserted in bosses and designed to be in alinement and in proximity with the aforesaid slots, a split gear-wheel bolted to the projecting flanges through the elongated slots, and a coacting gear meshing with the aforesaid gear, as and for the purpose specified.
- 35 4. In a power-transmitting device, the combination with a support and a car-wheel axle, a split hub having projecting flanges therefrom, a plurality of set-screws radially inserted through suitable bosses on said flanges in alinement with elongated slots in said flanges, a gear-wheel bolted to the projecting 40 flanges, a sleeve extending from the gear-wheel and surrounding the axle, a strap encircling the sleeve and provided with an extension, and a coacting gear suitably journaled in said extension, as and for the purpose specified.
- 45 5. In a power-transmitting device, the combination with a support and a car-wheel axle, of a split hub having projecting flanges therefrom, a gear-wheel attached to the projecting flanges, means for centering the gear with the axle, a sleeve extending from the gear and surrounding the axle, a strap encircling the sleeve and having a projection therefrom, and a coacting gear journaled 50 therein, as and for the purpose specified.
- 55 6. In a power-transmitting device, the combination with a support and a car-wheel axle, of a split gear-wheel, a separable split hub therefor, adjustable means for attaching the 60 split gear to the split hub, a split sleeve extending from the halves of the gear, a strap encircling the sleeve, and having a projection, a coacting gear journaled in said projection, and means for adjustably supporting 65 the said projection, as and for the purpose specified.
7. In a power-transmitting device, the combination with a support and a car-wheel axle, of a split gear-wheel, a separable split hub therefor, adjustable means for attaching the 70 split gear to the split hub, a split sleeve extending from the halves of the gear, a strap having a rigid projection therefrom, a coacting gear journaled therein, and a swinging support for the rigid projection, as and for the 75 purpose specified.
8. In a power-transmitting device, the combination with a support and a car-wheel axle, of a gear-wheel designed to rotate with the axle, a sleeve extending from the gear, a strap 80 encircling the sleeve, and an arm rigidly attached to the strap, and a support for the arm designed to allow any movement of translation in the car-axle, as and for the purpose specified.
- 85 9. In a device of the class described, a split hub having projecting flanges therefrom, provided with elongated slots in a direct radial line with the center of the car-axle, bolts in said slots, a plurality of set-screws inserted 90 in bosses in proximity to the slots, and designed to continuously abut said bolts, a gear-wheel bolted to the sides of the flanges, and a coacting gear suitably journaled and supported, as and for the purpose specified.
- 95 10. In a device of the class described, a split gear having a sleeve extending in halves from each of its parts, and designed to rotate therewith clear of the car-axle, a separable split hub, a coacting gear, a strap encircling the 100 aforesaid sleeve and having an extension therefrom designed to support the coacting gear, as and for the purpose specified.
11. In a device of the class described, an adjustable and swinging support, comprising 105 a pair of suspended rings and designed to have a lateral movement, a rod journaled in the rings, a thimble located in the rod between the rings, a rod projecting through the thimble and suitable spiral springs designed 110 to form a cushion on each side thereof, a sleeve connected to the rod projecting through the thimble, and a plurality of gears, as and for the purpose specified.
- 115 12. In a device of the class described, in combination a split hub having projecting flanges and radial adjusting-slots therein, a plurality of set-screws in direct radial line with the slots and in proximity thereto, bolts 120 cooperating with said set-screws, a split gear 125 having a split sleeve extending therefrom, a strap encircling the sleeve, an arm rigidly attached to the strap, a coacting gear, a driving-shaft turned by said gear, and a support for the arm, adjustable to its various positions, 130 as and for the purpose specified.
13. In a device of the class described, in combination, a car-wheel axle suitably journaled, a gear with a sleeve extending therefrom, designed to surround the axle and leave 135 a clear space between, a separable hub with adjustable slots designed to carry the gear in its rotation on the axle, a strap encircling the sleeve, a coacting gear journaled in an exten-

sion from the strap, a swinging support for the arm, and a suitable driving-shaft driven by the coacting gear, as and for the purpose specified.

5 14. In a power-transmitting device, the combination with a car-wheel axle, suitably journaled, of a gear-wheel, a separable hub therefor, means for attaching the gear to the hub, a sleeve extending from the gear-wheel 10 and designed to surround the axle, a strap encircling the sleeve and having a projection, a coacting gear-wheel journaled in said projection, and suitable means for supporting the coacting gear, as and for the purpose specified.

15 15. In a device of the class described, in combination a car-wheel and axle thereof, a split hub securely bolted on the said axle and provided with extending flanges, a split gear 20 having projections therefrom parallel with the axle, and designed to be held clear of the same by the split hub, an arm having a ringed

end encircling the said projections, a support for the arm designed to allow any movement of translation in the car-axle, a coacting gear 25 and a suitable driving-shaft rotated by said gear, as and for the purpose specified.

16. In a device of the class described, in combination, an axle, a gear-wheel designed to rotate with the axle, a strap encircling the 30 axle in proximity to the gear-wheel, an arm rigidly attached to the said strap and a co-acting gear journaled therein, and a support for the arm designed to allow any movement of translation in the car-axle, as and for the 35 purpose specified.

Signed at Montreal, in the district of Montreal, in the Province of Quebec, Canada, this 15th day of May, 1902.

ISIDOR DEUTSCH.
